VACUUM SEALING MACHINE

Herbert A. Barnby, Toledo, Ohio, assignor to
 Owens-Illinois Glass Company, a corporation
 of Ohio

Application September 20, 1934, Serial No. 744,857

16 Claims. (Cl. 226—82)

My invention relates to improvements in vacuum sealing machines and more particularly to that type designed for tightening screw caps on glass jars and the like containers during the vacuumizing process.

Insofar as I am aware it is the general practice in vacuumizing and sealing containers, more especially glass jars, to place them in their entirety within a vacuum chamber and thereafter quickly exhaust the air from said chamber and container by instantaneous application of the highest available vacuum. This procedure is objectionable for two reasons, first, because it necessitates vacuumizing an unnecessarily large space to create a vacuum in the containers and, second, because the rapid exhaustion of air from the containers, where the contents are in powdered form, tends to and generally does draw some of the contents between the sealing gasket and sealing surface of the jar where they become lodged and prevent effective sealing engagement between the gasket and jar.

This latter phenomenon is especially true in the packaging of granulated coffee wherein the container or jar employed is provided with a relatively large orifice, and the correspondingly large closure or lid is loosely positioned on the jar preparatory to the vacuumizing and lid-tightening operation. It has been found that a sudden application of a high vacuum causes the lid to raise from the jar with an accompanying sudden exit or leaping out of the coffee through the larger orifice which the lid affords between its inner lining and the sealing surface of the jar.

An object of the present invention is to avoid the first of the above noted objections by materially reducing the volume from which the air must be exhausted in order to vacuumize the containers, and the second thereof by controlling the application of vacuum in a fashion to prevent undue agitation of the contents and escape of such contents through a passageway which is created by lifting of the closure under influence of the vacuum applied. To this end the vacuum chambers which are individual to the containers being vacuumized, are of such area that they may accommodate only the neck of the jars and closures together with a device for rotating and thereby tightening the closures. Moreover, the means for controlling the application of vacuum is such that a very low vacuum is applied at the beginning of the vacuumizing operation, the degree being gradually and progressively increased as the vacuumizing operation progresses with-

out equalization of the vacuum applied to the several heads or chambers. I am aware that in the vacuumizing and sealing of narrow neck containers wherein the closure or cap is crimped to the container closely enough that the problem of leakage by dusting of the product does not occur, a two-stage method of vacuumizing is sometimes employed. In such cases, however, the two stages of vacuum are employed merely in the attainment of a very high vacuum and not for the purpose of preventing leaping out of the product dust.

Because of the fact that there is no equalization between the vacuum applied to the several heads or chambers, the tendency of the high degree of vacuum created in the jars about to leave the apparatus to become "diluted" by the presence of air in the jars entering the apparatus, is eliminated.

Another object is the provision in apparatus of the above character of means whereby the vacuum chamber and jar to be vacuumized co-operate with each other in sealing the chamber preparatory to the removal of air therefrom and in which such cooperation of the chamber and jar effectively holds the jar against rotation about its own axis and thereby facilitates application and tightening of the jar closure. To this end the vacuum chamber consists of an inverted cup-like element having a sealing gasket of rubber or other suitable material about its lower margin in position to be forced into sealing contact with the shoulder or other desired surface of the jar.

A further object is the provision in apparatus of the above character of a closure applying and tightening device disposed within a vacuum chamber such as that just referred to and operated by mechanism including means which will automatically render said mechanism ineffective after the closure has been completely applied and sufficiently tightened.

Other objects will be in part apparent and in part pointed out herein.

In the drawings:

Fig. 1 is a vertical central sectional view with parts in elevation.

Fig. 2 is a detail front elevational view of one of the heads of the machine.

Fig. 3 is a view similar to Fig. 2 showing parts broken away and in section and the closure applying device disengaged from the closure.

Fig. 3A is a sectional elevation taken along the line IIIA—IIIA of Fig. 3.

Fig. 4 is a detail vertical sectional view taken

along the line IV—IV of Fig. 5 showing the vacuum distributor head which appears at the upper end of Fig. 1.

Fig. 5 is a horizontal sectional view taken substantially along the line V—V of Fig. 4.

Figs. 6, 7, and 8 are sectional elevational views illustrating the successive operations involved in vacuumizing and sealing a container. Fig. 6 shows the jar and closure immediately upon being placed in the machine prior to upward movement relative to the vacuum chamber. Fig. 7 shows the upper end of the jar cooperating with the vacuum chamber in sealing the latter. Fig. 8 is a view similar to Fig. 7 showing the closure applying device in engagement with the closure.

Fig. 9 is a detail vertical sectional view with parts in section of another form of vacuum distributing head.

Fig. 10 is a fragmentary horizontal sectional view taken along the line X—X of Fig. 9.

Fig. 11 is a diagrammatic plan view illustrating the relation between the vacuum sealing machine and conveyors associated therewith.

Fig. 12 is a detail vertical sectional view with parts in elevation showing a closure applying and tightening device including a plain resilient disk designed to engage a closure having an unbroken top surface or button.

In more or less general terms my invention comprises an annular series of vacuumizing and sealing units each in itself a complete vacuum sealing device and including a vacuum chamber formed and adapted to enclose only the filling opening and a minor portion of the adjacent surfaces of the container and a closure for said opening. Provision is made whereby progressively increasing degrees of vacuum may be applied to the containers. Within each vacuum chamber is a closure applying device which, in the illustrated embodiment of the invention, assumes the form of a constantly rotating head connected to means for rotating it and periodically bringing it into operative engagement with a closure. Additionally, there is included means for so adjusting the vacuumizing and sealing units that containers varying in height and diameter may be accommodated.

The present machine (Fig. 11) is shown in conjunction with a conveyor system designed to deliver containers such as glass jars to the machine for vacuumizing and sealing and removing the vacuumized and sealed containers therefrom and transferring them to a packing room or other destination. This conveyor system includes a continuously moving horizontal conveyor 20 extending alongside of the machine. A star wheel 21 and guard rails 22 direct the containers to the machine while a star wheel 23 and guard rails 24 function to move the vacuumized and sealed containers from the machine to the conveyor 20.

The machine, according to the present disclosure consists of a rotary carrier 25 for the vacuum sealing units 26 which are arranged in an annular series on said carrier, the latter being mounted upon a stationary vertical central column 27 rising from a stationary base 28. This base includes a motor and gear housing 29 in the form of a vertical cylinder, the upper end of which is closed by a cap plate 30. A sleeve 31 formed integral with the plate 30 supports the central column 27 which is of tubular form and, as will be apparent hereinafter, incidentally constitutes part of the vacuum piping system. An annular exterior shoulder 32 on the column 27 rests upon

the upper end of the sleeve 31. A nut 33 threaded upon the reduced lower end of the column firmly secures it to the plate 30.

The carrier 25 for said vacuum sealing units includes a base plate 34, lower spider 35, and upper spider 36 which are connected together for rotation about the central column 27, said base plate 34 and lower spider 35 being adjustable vertically relative to each other to compensate for differences in the height of containers being vacuumized and sealed. These features will be apparent presently.

The base plate 34 which is of disk-like form carries an annular series of container supports 37 which correspond in number to that of the vacuum sealing units and are mounted for vertical reciprocating movement independently of each other and the base plate. Each of these supports consists of a horizontal disk 38 attached to the upper end of a vertical push rod 39 which is slidingly fitted in and splined to a sleeve 40 depending from a marginal portion of the base plate 34. A cam roller 41 at the lower end of the push rod rides upon a stationary cam 42 which encircles the sleeve-like housing 29 of the base and is shaped to impart vertical movement to the series of container supports in synchronism with the operations of other parts of the machine.

Rotation of the base plate 34, and consequently the carrier 25, is obtained by mechanism including a ring gear 43 attached to the lower side of the base plate and running in mesh with a pinion 44, the latter being secured to the upper end of a shaft 45. This shaft 45 is journaled in bearings 46 and carries a worm gear 47 meshing with a worm 48, the latter carried by a horizontal shaft 49 suitably journaled in bearings in the end walls of a gear housing 50. This shaft 49 is driven by an electric motor 51 operating through pulleys 52 and a belt 53 or the like which is trained over said pulleys. A spur gear 54 at the lower end of the vertical shaft 45 may be connected to the conveyor system in order to effect synchronized operation of the vacuum sealing machine and said conveyor system.

A sleeve 55 rises from the center of the base plate 34 and encloses a portion of the central column about which it is adapted to rotate, said sleeve extending into and being splined to a hub 56 on the lower spider 35. This spider 35 is adjustable vertically relative to the sleeve 55 and, therefore, said base plate 34, for the purpose of changing the spaced relation between vacuum chambers 57 carried by said spider 35 and the container supports 38 to the end that containers of different height may be accommodated. The construction providing for such adjustment may consist of a collar 58 threaded upon the lower portion of the sleeve 55 and rotatively connected at its upper end to said lower spider 35 by means of a flange 59 and ring 60. A hand wheel 61 carried by said collar 58 facilitates rotation of the latter and consequent vertical adjustment of the lower spider on said sleeve. The upper spider 36 is rotatively mounted upon a stationary bearing 62 which is provided at the upper end of a sleeve 63, the latter being secured by a key 64 or spline to a tube 65, and said tube in turn being secured to the central column 27 by means of a pin 66. The lower and upper spiders 35 and 36 are rigidly connected together by tie-bolts 67 and together with a ring gear 68 and cam 69, the latter carried by the sleeve 63, are adapted for unitary vertical adjustment by means of said hand wheel 61. The ring gear is mounted be-

tween the hub 56 and sleeve 63 and is rigidly and nonrotatively connected to the latter by means of the key 64 referred to above.

Each vacuum sealing unit 26 includes a vacuum chamber 51, a closure applying device within the chamber, and means arranged above the chamber for operating the closure applying device. The vacuum chamber 51 includes a sleeve-like housing 70, the bore of which is of slightly greater diameter than the neck N and cap C or closure, of the jar J which is to be vacuumized and sealed. Moreover, the lower end of the bore may be and preferably is tapered so that when the chamber is brought into operative position with respect to the jar said tapered walls if necessary will center the jar relative to the axis of the chamber with the neck portion of the bottle extending into the chamber. At the bottom end of the chamber is arranged a combined sealing and gripping ring 71, this ring being preformed to substantially conform to the contour of the surface to be engaged thereby. This ring is attached to the lower end of the vacuum chamber by means of a flanged collar 72 and performs the two-fold function of creating an effective seal between the shoulder portions of the jar and the adjacent end of the vacuum chamber and so effectively gripping the jar and cooperating with the jar supporting disk 38 that the jar is held against rotation during the application of the cap or closure C. Moreover, the creation of a subatmospheric condition within the chamber operates to effect firm engagement between the jar and chamber and prevent relative rotation of the jar and chamber during tightening of the closure. This also lessens the pressure on the jar support and decreases crushing pressure on the jar shoulder. It will be observed that the vacuum chamber (Fig. 2) includes an attaching flange 13 which is secured to the lower side of the lower spider 35 by bolts 14 or like fasteners. In one wall of this vacuum chamber there is provided a vacuum port 15 connected through a hand valve 76 to a supply pipe 77 which extends upwardly and radially inward to a vacuum distributing head 78, which, as has been stated rather generally heretofore, is so constructed that it causes application of vacuum to the chamber and jar in progressively increasing degrees. Thus by applying a comparatively low vacuum at the outset and stepping it up by degrees, undue agitation of the contents and the consequent objectionable results pointed out heretofore are avoided.

The vacuum distributing head includes a drum-like chamber 79 threaded upon the upper end of the central column 27 and communicating with the interior of the latter which in turn is connected at its lower end to a vacuum supply pipe 80. A series of circumferentially spaced vacuum ports 81 (Fig. 5) graduated in size and increasing in diameter in the direction of travel of the carrier 25, are formed in the wall 82 of the chamber 79, said ports opening into the interior of the chamber and providing communication between the latter and a series of chambers 83, which one at a time, register with ports 84 in a rotary cap 85, said cap being rotatively telescoped over the chamber and said ports 84 in the cap connected to said vacuum pipes 77. The chamber and cap are connected together by a stub shaft 90 rising from the chamber and projecting upwardly through an opening in said cap. A spring 91 encircles the shaft and is held thereon by a nut 92.

An elongated arcuate channel 86 is provided 75 in the exterior surface of the chamber 79, one

end of said channel being disposed in proximity to the largest of the series of graduated ports 81. This channel has independent direct connection to a vacuum supply pipe 87 by way of pipes 88, one of which extends completely and longitudinally through the central column 27. An air admission port 89 (Figs. 1 and 5) is formed in the wall 82 of the chamber 79 and operates to open the vacuum pipes 77 one at a time to the atmosphere for the purpose of breaking the vacuum in the chambers 51. Thus it may be seen that rotation of the carrier 25 and said cap 85 in a clockwise direction relative to the chamber 79 brings the ports 84 one at a time into register with the graduated ports and effects application of vacuum to the chamber 51 and thereafter into communication with the channel 86 and finally into communication with the port 89. Such operation effects application of vacuum to the chambers in gradually increasing degrees and finally through the channel 86 the application of the highest available vacuum. Upon completion of the vacuumizing operation the ports 84 are brought one at a time into register with the port 89 through which air enters to fill the vacuum chambers. 25 Prior to reaching the point at which the pipes 77 register with the port 89, the closures C are completely applied and tightened to the jar, it being understood that these closures are loosely attached to the jar necks while moving along the conveyor 20 or prior to being placed thereon. Incidentally the upper spider 36 carries a post 93 (Figs. 1 and 5) which engages an adjustable set screw 94 on an arm 95 extending radially from the cap 85.

Each closure applying mechanism, in the event it is being used to tighten closures having a knife channel K or groove in their upper side, (substantially as shown in Carvalho Patent #1,912,969 dated June 6, 1933) consists of a rotary head 98 40 which is arranged in the upper portion of the corresponding vacuum chamber 51. A sealing gasket 99 disposed within the upper end of the chamber and contacting the rotary head 98 prevents leakage of vacuum at this point. Attached to the lower side of the rotary head 98 (Figs. 3 and 3A) and telescoped therein is a flanged disk 100 formed on its lower side with a pair of bosses 101 designed for engagement with the grooved closure. Such engagement involves projection 50 of the bosses into the channel K and is obtained by lowering of the head 98 under influence of the cam 69. This disk is splined to the head 98 and yieldingly connected thereto by means of a screw 102 and coil spring 103 encircling said screw. 55 Thus the disk is free to move vertically upward relative to the head upon application of a predetermined top pressure to the latter.

This head 98 and the disk 100 are rotated continuously by mechanism including a shaft 104 60 which is secured at its lower end to said head 98 and has its upper end journaled in a bearing 105 forming a part of a cross head 106. Within this bearing 105 and interposed between the latter and said shaft 104 is a sleeve 107 which 65 carries one disk 108 of a friction clutch 109. A nut 104^a on the upper end of the shaft 104 and a collar 107^a just below said nut and carried by the sleeve 107 assist in holding the parts assembled. A key 110 connects said sleeve 107 and shaft 104 so that they rotate together. The other clutch member 111 is provided with a hub 112 freely rotatable on the shaft 104, said hub assuming the form of a spur gear meshing with the ring gear 68. This ring gear as will be understood 70 75

does not rotate. A disk 113 of suitable facing material is attached to one of the clutch disks for the purpose of creating driving connection between said disks and transmitting rotary motion from the hub 112 to the disk 100 which engages the closure.

Periodically during continuous rotation of the closure applying device it is moved vertically for the purpose of bringing the bosses 101 on the disk 100 into operative engagement with the closure. The mechanism for effecting such movement of the head 98 consists of a cam roller 114 attached to the inner side of the cross head 106 in position for engagement with the cam 69, said 15 cam being shaped to move the head 98 downwardly through yielding connectors consisting of a coil spring 115 encircling the shaft 104 between upper and lower collars 116 and 117 respectively, the former being loosely mounted upon the shaft 20 while the latter is threaded thereon. An anti-friction bearing 118 is interposed between the upper collar 116 and said hub 112.

Return movement of the head 98 to its uppermost position is effected by mechanism including guide rods 119 attached to the opposite ends of the cross head 106, said rods having their opposite ends slidably engaged in guide openings 120 in the upper and lower spiders and having coil spring 121 encircling the lower portions between collars 122 and the lower spider 35.

In operation, the carrier 25 is rotated continuously in a clockwise direction. Containers such for example as jars, are placed upon the supports 37 by means of the star wheel 21. At a predetermined point in the travel of the carrier the supports are moved vertically upward bringing the jars thereon into firm sealing contact with the combined sealing and gripping ring 71, the pressure of the latter upon the jar being sufficient to prevent rotation of the jar on its support and relative to the vacuum chamber 57 during the closure applying operation. Vacuum is applied to the vacuum chamber 57 and interior of the jar by way of said series of graduated ports 81 and the pipes 77. The highest available vacuum is then applied to said chamber and jar by way of the channel 88 and the ports 84, this taking place during the tightening of the closure C. At this point the cam 69 operates through the cam roller 114 to bring the continuously rotating head 98 into engagement with the closure. When the closure has been tightened to the necessary degree the friction clutch 109 slips and automatically breaks driving connection between said head 98 and the ring gear 68. Following this operation the closure applying head 98 is released and allowed to move upwardly under influence of the coil springs 121. Air enters the vacuum chamber by way of the port 89 and the corresponding vacuum pipe 71.

In another form of vacuum distributing head (Figs. 9 and 10) the construction includes a pair of upper and lower disks 123 and 124 respectively, the latter designed for attachment to the upper end of the central column in the same fashion as is the chamber 79. In this lower disk there is formed a series of circumferentially spaced graduated ports which establish communication between the interior of the central column and a series of chambers 126 which open through the upper side of said lower disk and are adapted for register with ports 127 in the upper disk. These ports 127 correspond in number to that of the pipes 77 which lead to the vacuum chambers 51. The full available vacuum is applied to the

chambers by way of a passageway 128 which is connected to a vacuum pipe 129 corresponding to the pipe 88 in the previously described form of head. The two disks are connected together by means including a stub shaft 130 rising from the center of the lower disk and projecting through an opening 131 in the upper disk. A coil spring 132 encircles the shaft 130 between an antifriction bearing 133 and a lock nut 134, said spring 10 yieldingly holding the disks in snug engagement with each other. An oil cup 135 or other similar device may be mounted upon the upper disk for the purpose of lubricating the contacting faces of said disk.

In Fig. 12 I have shown a slightly modified 15 form of closure applying device wherein the flanged disk 100, instead of being provided with bosses on its lower face, carries a friction gripping disk 136 which may be formed of rubber or any equivalent composition. These two disks 20 100 and 136 are secured together by screws 137 or the like fasteners. This form of closure applying device is particularly adaptable for tightening closures which are not provided with grooves, bosses or the like on their upper surface 25 and wherein friction alone must be relied upon to effect driving engagement between the head and closure.

Modifications may be resorted to within the spirit and scope of the appended claims. 30

What I claim is:

1. In a vacuum sealing machine, a support for a container to be vacuumized and sealed, an inverted cup-like vacuum chamber adapted to enclose a portion of the container, a sealing ring at the lower margin of the chamber, means for effecting relative vertical movement between said support and chamber to thereby bring the sealing ring and container into engagement with each other, a continuously rotating device within the chamber for applying a closure to the container, means for bringing said device into engagement with the closure, means for applying progressively increasing degrees of vacuum to the container and chamber and means for rotating the closure applying device including a friction clutch operating to render the closure rotating means ineffective upon completion of the closure applying operation. 40

2. In a vacuum sealing machine, a support for a container having a filling opening at its upper end, an inverted cup-like vacuum chamber adapted to enclose the filling opening and a closure for said opening, a sealing ring at the lower margin of said chamber, means for effecting relative vertical movement between said support and chamber to thereby bring the ring and container into sealing engagement with each other, means within said chamber for applying the closure to the container, means for applying progressively increasing degrees of vacuum to the container and chamber, said closure applying means including a continuously rotating device adapted for engagement with the closure, and means including a friction clutch for rotating said device. 50

3. In a vacuum sealing machine, a support for a container to be vacuumized and sealed, said container having a filling opening at its upper end and a closure partially applied thereto, a vacuum chamber adapted to enclose said filling 70 opening and closure and have sealing engagement with portions of the container about the opening, means within said chamber for completing application of the closure to the container, means for exhausting the air from said chamber and 75

5 container, said closure applying means including a continuously rotating head adapted to engage the closure, means for bringing said head into contact with the closure, and means providing vertically yielding connection between the head and rotating means.

4. In a vacuum sealing machine, a carrier mounted for rotation about a vertical axis, an annular series of container supports thereon, 10 vacuum chambers individual to and spaced above said supports, said chambers adapted to enclose only a portion of the containers on said supports, means for bringing the chambers and containers into cooperative relation to each other, means for 15 exhausting the air from the chambers and containers during a portion of each revolution of the carrier, means within the chambers for applying closures to the containers, each of said closure applying means including a head arranged within 20 the corresponding vacuum chamber, means for imparting continuous rotary movement to the head, and means for bringing the head into operative engagement with a closure on a container and means providing vertically yielding connection 25 between the head and rotating means therefor.

5. In a vacuum sealing machine, a carrier mounted for rotation about a vertical axis, an annular series of container supports thereon, 30 vacuum chambers individual to and spaced above said supports, said chambers adapted to enclose a minor portion only of containers arranged upon said supports, means for bringing the chambers and containers into cooperative relation to 35 each other, means for exhausting the air from the chambers and containers during movement of the carrier, means within the chambers for applying closures to the containers, each of said closure applying means including a head arranged within 40 the corresponding vacuum chamber, means for imparting continuous rotary movement to the head, means for bringing the head into operative engagement with a closure on a container, and a friction clutch constituting part of the head rotating means and operating to 45 render the latter ineffective upon completion of the closure applying operation.

6. In a vacuum sealing machine, a vacuum chamber adapted to enclose the filling opening and at least a portion of the adjacent surface of 50 a container to be vacuumized and sealed, means for applying progressively increasing degrees of vacuum to the chamber and container, a closure applying device within the vacuum chamber including a rotary head, means for bringing the head into engagement with a closure on the container, a container support below the vacuum chamber, a combined sealing and gripping ring carried by the vacuum chamber adapted to 55 cooperate with said support in holding the container against rotary movement relative to the vacuum chamber, means for continuously rotating said head, and a vertically yielding connector between said head and its rotating means.

65 7. In a vacuum sealing machine, a vacuum chamber adapted to enclose the filling opening and at least a portion of the adjacent surface of a container to be vacuumized and sealed, means for applying vacuum to the chamber and container, a closure applying device within the vacuum chamber including a rotary head, means for bringing the head into engagement with a closure 70 on the container, a container support below the vacuum chamber, a combined sealing and gripping ring carried by the vacuum chamber and 75

adapted to cooperate with said support in holding the container against rotary movement relative to the vacuum chamber, means for continuously rotating said head and a vertically yielding connector between said head and its rotating means.

8. In a vacuum sealing machine, a support for a container to be vacuumized and sealed, an inverted cup-like vacuum chamber adapted to enclose a portion of the container, a sealing ring 10 at the lower margin of the chamber, means for moving the container support vertically upward to thereby bring the sealing ring and container into engagement with each other, a rotatable device within the chamber for tightening a threaded closure upon the container, means for bringing said device into engagement with the closure, means for applying progressively increasing degrees of vacuum to the container and chamber, a vertically yielding connector between the closure applying device and the means for bringing it into engagement with the closure, and means for rotating said device.

9. In a vacuum sealing machine, a support for a container to be vacuumized and sealed, an inverted cup-like vacuum chamber adapted to enclose a portion of the container, a sealing ring at the lower margin of the chamber, means for effecting relative vertical movement between said support and chamber to thereby bring the sealing ring and container into engagement with each other, a device within the chamber for tightening a closure to the container, means for bringing said device into engagement with the closure, means for exhausting the air from said container and chamber, a vertically yielding connector between the closure applying device and the means for bringing it into engagement with the closure, and means for rotating the device including a friction clutch operable to render the 40 rotating means ineffective upon completion of the closure applying operation.

10. In a vacuum sealing machine, a support for a container to be vacuumized and sealed, an inverted cup-like vacuum chamber adapted to enclose a portion of the container, a sealing ring at the lower margin of the chamber, means for effecting relative vertical movement between said support and chamber to thereby bring the sealing ring and container into engagement with each other, a device within the chamber for tightening a closure to the container, means for bringing said device into engagement with the closure, means for applying progressively increasing degrees of vacuum to the container and chamber, a vertically yielding connector between the closure applying device and the means for bringing it into engagement with the closure, and means for rotating the device including a friction clutch operable to render the rotating means ineffective upon completion of the closure applying operation.

11. In a vacuum sealing machine, a vacuum chamber adapted to enclose the filling opening and at least a portion of the adjacent side surface of a container to be vacuumized and sealed, means for applying vacuum to the chamber and container, a closure applying device within the vacuum chamber including a rotary head, means for bringing the head into engagement with a closure on the container, a container support below the vacuum chamber, a combined sealing and gripping ring carried by the vacuum chamber and adapted to cooperate with said support in holding the container against rotary movement

- relative to the vacuum chamber, means for rotating said head including a pinion individual thereto and clutch means for effecting driving connection between the pinion and head at intervals 5 and means for rotating the pinion.
12. In a vacuum sealing machine for vacuumizing containers and tightening threaded closures thereon, the combination of an annular series of container supports mounted for rotation about a vertical axis, inverted cup-like vacuum chambers individual to said supports and arranged thereabove and in alignment therewith, a combined sealing and gripping ring at the lower margin of each vacuum chamber, mechanical means for relatively moving each support and the corresponding vacuum chamber to thereby effect such engagement between a container and said ring that said container is held against rotation about its own axis, a rotary closure applying device 10 within each vacuum chamber, means for rotating said devices, cam means for successively urging said devices into yielding frictional engagement with respective closures on said containers, means whereby said rotating means becomes 15 operative with respect to each individual closure applying device when the closure engaged thereby is tightened on its respective container, and means for exhausting air from said chambers.
13. In a vacuum sealing machine, a vacuum chamber adapted to enclose the filling opening and at least a portion of the adjacent surface of a container to be vacuumized and sealed, means for applying vacuum to the chamber and container, a closure applying device within the vacuum chamber including a rotary head, means for bringing the head into engagement with a closure on the container, a container support below the vacuum chamber, a combined sealing and gripping ring carried by the vacuum chamber and adapted to cooperate with said support in holding the container against rotary movement relative to the vacuum chamber, means for rotating said head including a vertical spindle carrying said head, a pinion mounted for free rotation on said spindle, clutch means for effecting a driving connection between said pinion and spindle at intervals, and a ring gear meshing with said pinion. 20
14. In a vacuum sealing machine, a stationary base, a vertically extending central column projecting upwardly from said base, a rotary carrier mounted on said column, a plurality of vacuum sealing units mounted on said carrier, each unit including a chamber for vacuumizing a container, an annular vacuum distributing head providing a vacuum chamber mounted on said column, means connecting said chamber with a source of relatively low vacuum, there being a plurality of circumferentially spaced vacuum ports extending through said head and communicating with the interior of said chamber, said ports being graduated in size and increasing in diameter in the direction of travel of said rotary carrier, there being an elongated arcuate vacuum 25
- channel formed in said head, means connecting said channel with a source of relatively high vacuum, a cap mounted on said head for rotation with said carrier, said cap having a plurality of ports therein communicating with the vacuum chambers of said sealing units and adapted first to successively register with said vacuum ports and finally with said vacuum channel, and means for rotating said carrier. 30
15. In a vacuum sealing machine, a stationary base, a vertically extending central column projecting upwardly from said base, a rotary carrier mounted on said column, a plurality of vacuum sealing units mounted on said carrier, each unit including a chamber for vacuumizing a container, an annular vacuum distributing head providing a vacuum chamber mounted on said column, means connecting said vacuum chamber with a source of relatively low vacuum, said head having a plurality of circumferentially spaced vacuum ports extending therethrough and communicating with the interior of said vacuum chamber, said ports being graduated in size and increasing in diameter in the direction of travel of said rotary carrier, there being an elongated arcuate vacuum channel formed in said head, means connecting said channel with a source of relatively high vacuum, there being an air admission port in said head, a cap mounted on said head for rotation with said carrier, said cap having a plurality of ports therein communicating with the vacuum chambers of said sealing units and adapted first to register successively with said vacuum ports, secondly with said vacuum channel, and lastly with said air admission port. 35
16. In a vacuum sealing machine, a stationary base, a vertically extending central column projecting upwardly from said base, a rotary carrier mounted on said column, a plurality of vacuum sealing units mounted on said carrier, each unit including a chamber for vacuumizing a container, an annular vacuum distributing head providing a vacuum chamber mounted on said column, means connecting said vacuum chamber with a source of vacuum, said head having a plurality of circumferentially spaced vacuum ports extending therethrough and communicating with the interior of said vacuum chamber, said ports being graduated in size and increasing in diameter in the direction of travel of said rotary carrier, there being an elongated arcuate vacuum channel formed in said head, means connecting said channel with a separate source of vacuum, there being an air admission port in said head, a cap mounted on said head for rotation with said carrier, said cap having a plurality of ports therein communicating with the vacuum chambers of said sealing units and adapted first to register successively with said vacuum ports, secondly with said vacuum channel, and lastly with said air admission port. 40
